WASHING MACHINE PROVIDED WITH
RESILIENT AGITATORJohn A. Castricone, Peoria, Ill., assignor to
Altorfer Bros. Company, Peoria, Ill., a corpora-
tion of Illinois

Application November 1, 1949, Serial No. 124,739

8 Claims. (Cl. 68—133)

1

This invention relates to a device for distributing the clothes in a washing machine tub to provide an equal distribution of clothes around the tub wall for more effective washing and further provides a balanced load of such clothes in the tub.

The device is an improvement on my orbital dasher washer as disclosed in my Patent 2,416,611, issued February 25, 1947, which clearly describes the orbital dasher employed in this improvement.

The particular object of this invention is to provide an extended clothes contacting vane on the dasher to assist in the equalized re-distribution of the clothes in the tub for washing and a balanced division of the clothes in the tub. A still further object is to provide a flexible vane on an orbital dasher of the washing machine that will prevent damage to clothes while assisting in a re-location and equal re-distribution of the clothes in the tub.

Other objects and benefits will be disclosed in the following descriptions and drawings in which:

Fig. 1 is a front elevational cross sectional view of a preferred form of a washing machine employing my improved dasher;

Fig. 2 is a plan sectional view of the washer shown in Fig. 1 as it would appear on the section lines 2—2 of Fig. 1;

Fig. 3 is an enlarged plan view of the washer tub in section showing flexible vanes attached to the dasher as they would appear in contact with the clothes;

Fig. 4 is an enlarged plan view, partly in section, of a flexible rubber vane attached to the vane of the dasher;

Fig. 5 is a similar view of the vane in Fig. 4 as it would appear in flexed position when in contact with the clothes.

Fig. 6 is a plan view of another form of vane wherein a metallic vane is attached to a rubber attachment member as it would normally appear; and

Fig. 7 is another view of the vane shown in Fig. 6 as it would appear in angular flexed position when in contact with clothes.

Now referring to the drawings and at the outset to Figs. 1 and 2, I show an outside frame 10 and carrying a base support member 11 hung by flexible support members 12, 13 and 14 from the frame 10. On the base 11 is mounted a stationary outside tub 15 and within the tub 15 is a rotatable tub 16 having extractor holes 16—h, in its top periphery. The tub 16 is carried on

2

a drive mechanism 17 which rotatably supports the tub 16 and dasher 19 which may be rotated by the motor 18 either with the dasher 19 being orbitally rotated separately or the tub 16 and the dasher 19 being rotated together. Aside from the orbital dasher mechanism fully described in my Patent No. 2,416,611, the above mechanism has no bearing on the present invention and will not be described in detail except to explain that the dasher drive is revolved at about 300 R. P. M. and the tub at about 600 R. P. M.

It should further be explained that the above described washing machine is what is known as an automatic washer, that is, it automatically goes through time cycles of washing, rinsing and drying the clothes. In the first cycle, the wash water is placed in the tub and the dasher operated for say a ten minute cycle with the dasher being moved orbitally at about 300 R. P. M. Next, the wash water is extracted by rotating the tub at 600 R. P. M. Up to 300 R. P. M. the dasher continues to be orbitally moved while the major portion of the water is extracted. It will thus be carefully noted that up to 300 R. P. M. the dasher has a continued opportunity to act on the clothes. Next, the tub is filled with rinse water and the dasher continues to rotate as a power rinse for three minutes. Then the first rinse water is extracted. Then, subsequently, one or two further rinse operations are performed with extraction of rinse water between each operation. Finally the clothes are thoroughly extracted and the clothes removed. Thus it will be apparent that three or four extracting cycles are performed and it is highly necessary to place the clothes in balance in the tub so that the tub may be rotated at high speed. Most automatic machines shut off the power circuit when the tub is seriously out of balance. Thus the operator is often disappointed and disgruntled upon returning to find that her washing is incomplete. It is almost impossible for the operator to rearrange the clothes in balance on her first trial, so it will be appreciated that automatic balancing of the load is most advantageous and desirable.

Now referring to Fig. 3, I have shown an unbalanced load of clothes C1 around the inner wall of the rotating tub 16 which is enclosed within the stationary tub 15. The two tubs are supported together on the base 11 by resilient swinging support rods 12, 13 and 14. It will be obvious that an unbalanced load of clothes C1 would cause excessive swinging of the entire machine on the support base 11 and this excessive swinging is

used to actuate the shut off switch. In a similar manner shut off switches are used on other types of extractor mountings to accomplish the same results.

Now again referring to Fig. 3, the dasher 19 moves in an orbital path O around the center C of the tub 16, and this orbital movement of the dasher 19 has the general effect of distributing the clothes around the inner wall of the tub 16 as indicated by the clothes area C1. However, when a dasher 19 is used with the vanes as described in my Patent No. 2,416,611, there sometimes occurs heavier sections of clothes like C1—h and adjacent to such heavier sections are lighter sections C1—l. The heavier sections of the clothes have a tendency to move slower than the lighter sections. It often also occurs that some sections of the clothes get filled with air, especially pillow cases, pockets, etc., and these balloon-like sections also have a tendency to retard the rotation of that section of the clothes. In order to improve the distribution of clothes in the tub, I have added resilient extension vanes 22 on three of the vanes as clearly indicated in Figs. 1 and 2. These vanes extend beyond the normal vanes of the dasher and as clearly indicated in Fig. 3, contact the heavier sections of clothes C1—h in a manner to cause the resilient vanes 22 to be bent or distorted without jamming or damage to the clothes. Now on the dasher 19 I have placed an arrow in Fig. 3 showing the manner in which the dasher 19 moves in an orbital path around the center of the tub C. With the vane 22 bent as shown and the movement of the dasher in the orbital path around the center C, the bent vanes 22 have the effect of moving the heavy section of clothes C1—h and distributing the heavier loads into the lighter sections C1—l. This action of the resilient vanes 22 is very effective in distributing the clothes uniformly around the inner wall of the tub 16 for more uniform washing and to effect a balanced load of clothes within about one minute of the operation of the dasher. I have previously described how the dasher 19 continues to operate as the water is extracted from the tub 16. This appears to effectively assist in the distribution of the clothes and I am enabled to get practically perfect balanced loads in a high percentage of cycles.

Now referring to Fig. 4, I show a resilient contact vane 22 preferably made of a relatively stiff but resilient rubber compound which is attached to a vane 19—v on the dasher 19 by a rivet or bolt connection 23. When the end of the resilient vane 22 contacts clothes as previously illustrated for Fig. 3, it assumes the bent position shown in Fig. 5 and the combination of the resilience of the vanes 22 with the orbital movement of the dasher 19 effects the equal distribution of clothes as previously described.

Now referring to Fig. 6, I show another form of resilient vane 24 which is made of stiff aluminum or plastic or the like. In this construction the vane 24 is attached to a resilient hinge 25 attached to the vane 19—v by riveted or bolted connections 23 and 23—a. Such a structure assumes a bent position as shown in Fig. 7 when it contacts the clothes around the periphery of the tub 16 and this resilient construction combined with the orbital movement of the dasher also is effective in distributing the clothes as previously described. There undoubtedly are other forms of resilient vane elements that may be utilized to effect the same results. It appears that the results are obtained by the resilience in the vane

after it contacts the heavy clothes loads to transmit the orbital movement of the dasher 19 to move the clothes around the periphery of the tub. I have found that many forms of resilient vanes can be used with good results, although the simple form of rubber vane as shown in Figs. 4 and 5 appear to get optimum results.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the forms hereinbefore described being merely preferred embodiments thereof.

I claim:

1. In a clothes balancing device for a washing machine having a tub for containing washing and rinsing water with the clothes, an integrally formed dasher, drive means continuously rotatable in one direction and having the dasher rotatably mounted on an upright axis, which axis is movable by said drive means in an orbital path within the tub, and resilient extension vanes on the dasher to flexibly contact the clothes within the tub beyond the orbital path of the dasher to effect an equalizing distribution of the clothes in the tub.

2. In a washing machine, a tub adapted to contain a body of water for washing clothes therein, a drive shaft extending upwardly in said tub, and a dasher surrounding said shaft and mounted thereon for free and independent movement relative to said tub, said shaft being connected with the dasher eccentrically of the shaft for moving the dasher bodily in an orbit relative to the axis of the shaft, said dasher having a body with a diametrically enlarged base portion with a diametrically reduced upper portion thereabove and rigid therewith, and resilient fins projecting outwardly from the body and spaced at intervals therearound throughout the major portion of the height of the body for producing an equalized distribution of the clothes around the tub.

3. In a washing machine, a tub adapted to contain a body of water for washing clothes therein, a drive shaft extending upwardly in said tub, and a dasher surrounding said shaft and mounted thereon for free and independent movement relative to said tub, said shaft being connected with the dasher eccentrically of the shaft for moving the dasher bodily in an orbit relative to the axis of the shaft, said dasher having a diametrically enlarged substantially cylindrical base portion of appreciable height with a diametrically reduced upper portion thereabove and rigid therewith, and vanes spaced at intervals around said upper portion and extending downwardly substantially to the base portion and having inwardly inclined outer edges, and resilient fins mounted on the vanes and projecting outwardly therefrom substantially throughout the height thereof for producing an equalized distribution of the clothes around the tub.

4. In a washing machine, a tub adapted to receive a body of water for washing clothes therein, an upright drive shaft, a dasher in the tub and connected with the drive shaft for movement continuously in one direction on an upright axis which axis is movable by said drive shaft in an orbital path relative to the axis of the drive shaft, and a plurality of resilient vanes on the periphery of the dasher in position to flexibly

contact the clothes in the tub to effect an equalized distribution of the clothes therein.

5. In a washing machine, a tub adapted to receive a body of water for washing clothes therein, an upright drive shaft, a dasher in the tub and connected with the drive shaft for movement continuously in one direction on an upright axis which axis is movable by said drive shaft in an orbital path relative to the axis of the drive shaft, said dasher having upwardly extending vanes spaced at intervals about the periphery thereof, and resilient vanes mounted on the upwardly extending vanes and projecting outwardly therefrom throughout a substantial portion of the height of the dasher for producing an equalized distribution of the clothes around the tub.

6. In a washing machine, a tub adapted to receive a body of water for washing clothes therein, an upright drive shaft, a dasher in the tub and connected with the drive shaft for movement continuously in one direction on an upright axis which axis is movable by said drive shaft in an orbital path relative to the axis of the drive shaft, said dasher having upwardly extending vanes spaced at intervals about the periphery thereof, and resilient vanes mounted on the upwardly extending vanes and projecting outwardly therefrom throughout a substantial portion of the height of the dasher for producing an equalized distribution of the clothes around the tub, each of said resilient vanes being formed of rubber yieldable transversely of the width thereof circumferentially of the dasher.

7. In a washing machine, a tub adapted to receive a body of water for washing clothes therein, an upright drive shaft, a dasher in the tub and connected with the drive shaft for movement continuously in one direction on an upright axis which axis is movable by said drive shaft in

10 an orbital path relative to the axis of the drive shaft, and a plurality of resilient vanes on the periphery of the dasher in position to flexibly contact the clothes in the tub to effect an equalized distribution of the clothes therein, each of said resilient vanes comprising a section on the dasher and a flexible section of resilient material extending outwardly therefrom and forming the outer portion of the vane in position to contact the clothes.

15 8. In a washing machine, a tub adapted to receive a body of water for washing clothes therein, an upright drive shaft, a dasher in the tub and connected with the drive shaft for movement continuously in one direction on an upright axis which axis is movable by said drive shaft in an orbital path relative to the axis of the drive shaft, and a plurality of resilient vanes on the periphery of the dasher in position to flexibly contact the clothes in the tub to effect an equalized distribution of the clothes therein, each of said vanes comprising a section on the dasher, a stiff section in position to contact the clothes and a resilient hinge section connecting said

20 first-mentioned and stiff sections together.
